Primary Examiner — Barbara Fox*Assistant Examiner* — Kristin E Reed(74) *Attorney, Agent, or Firm* — Design IP(57) **CLAIM**

The ornamental design for a wearable electronic device, as shown and described.

DESCRIPTION

FIG. 1 is a front, right perspective view of a first embodiment of a wearable electronic device showing my new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken line showing of portions of the wearable electronic device in FIGS. 1-7 is for the purpose of illustrating environmental structure and forms no part of the claimed design.

1 Claim, 5 Drawing Sheets(56)
